W. A. E. QUILTER

THERMIONIC DEVICE

Filed Feb. 26, 1921

Inventor
W. A. E. QUILTER
By his Attorney, *John J. Adams*

UNITED STATES PATENT OFFICE.

WILLIAM ALFRED EDWARD QUILTER, OF LONDON, ENGLAND, ASSIGNOR TO RADIO CORPORATION OF AMERICA, A CORPORATION OF DELAWARE.

THERMIONIC DEVICE.

Application filed February 26, 1921, Serial No. 448,232, and in Great Britain March 24, 1920.

This invention relates to thermonionic devices or valves, and its object is to provide a valve in which the size of the apertures in the grid can be adjusted for varying the 5 effect of the grid.

According to this invention I construct the grid of the valve of two parts capable of relative movement and I provide means for moving one of the parts relatively to 10 the other so that the apertures in the one part register more or less with the apertures in the other part, and thus the effective apertures of the whole grid are varied.

Preferably the grid consists of two co- 15 axial cylinders, the inner one of which is fixed, while the outer one can be turned round the common axis.

Each cylinder may conveniently be formed 20 of a helix of wire, the two helices being of the same pitch.

The invention is illustrated by way of example in the accompanying drawing, Figure 1 of which is a view partly in elevation and partly in section of a valve constructed 25 in accordance therewith; Figure 2 is a horizontal section on the line X—Y, Figure 1, and Figure 3 shows a modification.

The grid consists of two co-axial wire 30 helices of the same pitch: the inner one D, is fixed while the outer one C, is mounted between the top bearing B, and the bottom bearing E, and can be turned round the common axis.

The movement of the outer cylinder may 35 be effected by an electromagnet having a ring shaped core O, with a gap P, in it, while close to this core is a soft iron pole piece H, mounted on a rod G secured to the outer cylinder C, so that the position of the 40 outer cylinder depends upon the strength of the current through coil K, outside the valve glass bulb energizing the magnet.

The theory of operation of the modification shown by Figs. 1 and 2 is thought to 45 be as follows: The lines of force produced by the coil K tend to pass vertically downward thru the core O. However, the lines of force in the immediate vicinity of the air gap P will be curved to a considerable 50 degree. This distortion of the magnetic field in the vicinity of the gap P will cause a distortion of the entire magnetic field passing thru the core O. The magnetic field will therefore act on any magnetic body and will tend to move said body into a position

where the distortion is minimized or eliminated. The movement of the armature H toward the gap P will tend to minimize the distortion of the magnetic field. Upon the energization of coil K, the armature H will 60 accordingly be moved toward the air gap P.

Or the outer cylinder may be tied to a hot wire Q, so that the position of the cylinder depends upon the current passing through and heating the wire. 65

In either case a spring F is provided so as to tend to move the outer cylinder C in an anti-clockwise direction and thus control the rotation of the outer cylinder C by the electromagnet of the wire Q. 70

Having now particularly described and ascertained the nature of my said invention and in what manner the same is to be performed, I declare that what I claim is:—

1. A thermionic valve in which the grid 75 is constructed of a plurality of metallic parts having apertures, said parts being capable of relative movement one to the other, so that the effective apertures of the grid may be varied.

2. A thermionic valve in which the grid is constructed of a plurality of metallic parts each having similar apertures, said parts being capable of relative movement one to the other, so that the effective apertures of 85 the grid may be varied.

3. A thermionic valve in which the grid consists of two substantially co-axial cylinders having apertures, one of said cylinders being fixed and the other capable of movement around its axis, whereby the effective 90 apertures may be varied.

4. A thermionic valve in which the grid consists of two co-axial cylinders one with- 95 in the other, having apertures, the inner cylinder being fixed and the outer cylinder capable of movement around its axis, whereby the effective apertures may be varied.

5. A thermionic valve in which the grid is constructed of a plurality of metallic parts 100 having apertures, means for causing relative movement of said parts to vary the effective apertures of the grid, and means for returning the parts to their normal position.

6. A thermionic valve in which the grid is 105 constructed of two parts with co-axial spiral elements of the same pitch, said elements being capable of relative movement one to the other, so that the effective apertures of the grid may be varied. 110

7. A thermionic valve in which the grid is constructed of two parts having apertures, said parts being capable of relative movement one to the other, so that the effective apertures of the grid may be varied, and an electromagnet for producing said relative movement comprising an armature and a winding, one of which is attached to the movable part of the grid.
- 5 8. A thermionic valve in which the grid is constructed of two parts having apertures, said parts being capable of movement one to the other, so that the effective apertures of the grid may be varied, and means for causing said relative movement comprising an armature attached to the movable part of the grid and a stationary winding co-operating with said armature.
- 10 9. A thermionic valve in which the grid is constructed of a plurality of metallic parts having apertures and means for causing relative movement of said parts to vary the effective apertures of the grid.

WILLIAM ALFRED EDWARD QUILTER.
